UNITED STATES PATENT OFFICE.

LEONIDAS NORZAGARAY, OF LONDON, ENGLAND, ASSIGNOR TO THE ECONOMIC RUBBER WASHING MACHINE CO., LIMITED, OF LONDON, ENGLAND, A CORPORATION OF ENGLAND.

MACHINE FOR TREATING RUBBER.

1,110,340.

Specification of Letters Patent.

Patented Sept. 15, 1914.

Application filed December 11, 1911. Serial No. 665,111.

To all whom it may concern:

Be it known that I, LEONIDAS NORZAGARAY, a citizen of the Republic of Brazil, residing at 35 Hargrave Mansions, Hargrave 5 Road, Upper Holloway, London, England, have invented certain new and useful Improvements in Machines for Treating Rubber, of which the following is a specification.

This invention relates to machines for extracting rubber from bark and has for its 10 object to provide a machine of this character which is capable of cleansing crude rubber, as well as mixing or kneading and rolling and cutting the same.

15 Referring to the accompanying drawings, Figure 1 is a side elevation of my improved machine, partly broken away and partly in section. Fig. 2 is a section through the rotating cylinder.

20 Referring more particularly to the drawings the machine comprises an open top vessel *a*, the upper portion being cone-shaped and the lower portion of circular shape. The vessel *a* is provided with an outwardly 25 extending flange *c* which is bolted or otherwise attached to a stand *d*, preferably of metal. The interior of the vessel is grooved or corrugated forming a spiral thread *b*, and the lower end or circular portion of the 30 vessel terminates in a hollowed out portion *e* of the metal stand *d* which in reality forms the bottom of the vessel.

Within the open top vessel is arranged a rotatable cylinder or drum *f* of the same 35 height as said vessel. This cylinder may be either hollow or perforated and is provided on its outside with ribs or projections *g* forming a spiral thread. Perpendicular teeth *h* are also provided at intervals, between the teeth of the spiral ribs *g*. These 40 teeth are about half the thickness of the ribs *g* and consequently do not project outwardly from the face of the cylinder sufficiently far for their outer face to be flush 45 with the outer faces of the ribs. Alternatively the perpendicular teeth on the cylinder may be continuous and the spiral ribs consequently broken. Again each section 50 of the spiral ribs between two of the vertical ribs may be cut or notched vertically so as to form saw-like teeth.

The cylinder is furnished at the bottom of its periphery with one or more laterally

projecting teeth *i* and with perforations *j* for a purpose hereinafter described. Preferably the cylinder is attached to or may be an integral part of, a shaft *j* having a gear wheel *k* on its upper end engaging another gear wheel *l*, the latter being attached to a horizontal driving shaft *l* which is supported on the frame work *m* of the machine and driven from a suitable source of power. This cylinder shaft *j* projects beyond the bottom of the cylinder and the lower end thereof is housed in a chamber *n* formed in the machine stand. The chamber *n* extends through the stand (which is partly hollowed out at the bottom as previously described) and is fitted with a removable bearing *n* upon which the end of the shaft revolves. A bearing collar for the upper end of the shaft is attached to the frame work and directly beneath this collar is arranged an oil trap *o*.

A metal roller *p*, of about the same diameter as the spiral cylinder *f* is arranged immediately above said cylinder and attached to or formed integrally with the shaft *j*. This roller is provided with undercut teeth *p* at the bottom of its periphery. These teeth form a cutting gear wheel. A smaller roller *q* adjacent to the roller *p*, is also provided with projecting cutting teeth *q* adapted to mesh with the teeth *p*. The roller *q* is mounted in the frame of the open top vessel *a* and is provided with an oil trap *q*, bearing collar *q* and gear wheel *q*, the latter being arranged to mesh with the gear wheel *k* of the larger roller *p*.

A space as at *r* is created between the rollers as by making the teeth on the smaller roller or rollers of a greater depth than that of the teeth on the larger roller. This space may be varied by the substitution of other small rollers having teeth of a greater or lesser depth, or by employing gear wheels—capable of being removably attached to the small roller—having teeth of varying depth. Or I may make the larger roller quite plain and attach a cutting collar or collars to the bottom or bottoms of the smaller roller or rollers. In this case the space between the rollers will be regulated by employing rolls of a larger or smaller circumference. The larger roller 105 may have wording on its surface for mark-

ing the rubber sheets. The small roller may be either plain or corrugated. A collar *s*, fixed by means of a flange at its lower end to the top of the frame of the open topped vessel, partly surrounds the above mentioned rollers for a distance of about half their height. This collar has a side opening furnished with a guide (not shown) to allow of the egress of the finished rubber-sheets from the machine. A perforated pipe *s*¹ is arranged partly around the inside of the top of said collar, or the pipe may be made in one piece with the collar as shown in the drawings. This pipe is suitably connected to a liquid supply (not shown).

A feeding tube *t* of preferably conical shape, and of the same height as the open topped vessel is positioned in front of the latter and within the frame work of the machine, and is provided with a flange *t*¹ by means of which it is bolted to the stand, and has an opening *t*² at its lower end leading into the open topped vessel. A spindle or shaft *u*, revolving at its lower end upon a removable bearing *u*¹, arranged in the stand *d* of the apparatus, is partly housed in said feeding tube and is provided with a tapering feed worm *u*² of a length somewhat less than that of the tube. The upper end of the spindle or shaft is supported by a bearing collar *u*⁴, having an oil trap *u*³ beneath, attached to the frame work and is adapted to be rotated by a gear wheel *u*⁵ at its upper end which meshes with another gear wheel *l*² at the end of the horizontal driving shaft. A tap *v*, connected to a suitable liquid supply, is arranged over the mouth of the feeding tube. The entire apparatus—with the exception of the outer frame work—is surrounded by a steam or water jacket *w* to a height slightly less than that of the open topped vessel *a*. This jacket is attached to the stand by means of a flange provided on its lower end, which is bolted thereto as at *x*.

An aperture or passage is provided leading from the bottom of the vessel *a* and to the outside of the stand *d* and a tap or cock controls the out flow of liquid from this aperture.

The working of the apparatus is as follows: The steam or hot water jacket is prepared. The vessel *a* and tube *t* are charged with hot water or other suitable liquid by means of the perforated pipe *s*¹ and tap *v* until the liquid reaches the desired level. The cock or tap which controls the outlet of the aperture or passage leading from the bottom of the vessel is then opened to such an extent as to keep the liquid at this level thus insuring a continuously descending volume of clear liquid. The driving shaft *l* is put in motion and the cylinder *f*, rollers *p*, *q* and shaft *u* rotated. The material to be treated is continuously fed into the top of tube *t*,

forced down by the worm *u*² to the opening *t*², stirred up by the lateral tooth or teeth *i* on the cylinder and carried upward between the spiral thread *b* of the vessel *a* and the spiral ribs *g* and vertical teeth *h* on said cylinder, being pressed, rolled and masticated thereby. The mass thus treated emerges into the space between the roller *p* and collar *s*, it then being carried, under the rotary action of the moving parts, to, and delivered into the space *r*, where it is again subjected to pressure, and has impressed thereon, the indicia with which the roller *p* may be provided, said mass then being cut and finally conveyed out of the machine through the opening and guide in said collar above referred to, it being taken at this point and suitably disposed of by an attendant.

I claim—

1. In a machine of the class described, a conical feeding tube, a worm operating therein, a spirally threaded vessel of a shape partly conical and partly circular, communicating with said tube, a spirally threaded cylinder rotatable within said vessel, said cylinder having vertical teeth and a lateral tooth thereon, a large roller immediately above the cylinder provided with a toothed cutting wheel, a smaller roller adjacent said large roller and also provided with a toothed cutting wheel, a collar partly surrounding these rollers, provided with an outlet, a perforated pipe on said collar, and means for simultaneously rotating said spirally threaded cylinder and said worm. 95

2. In a machine of the class described, a conical feeding tube having an opening in the lower end thereof, a worm operating in said tube, a spirally threaded vessel communicating with the opening in said feeding tube, a spirally threaded cylinder rotatable within said vessel, said cylinder having vertical teeth and a lateral tooth thereon, a pair of rollers above the cylinder provided with intermeshing toothed cutting wheels, and a collar partly surrounding these rollers provided with an outlet, means on said collar for supplying liquid to said vessel, and means for simultaneously rotating said spirally threaded cylinder and said worm. 110

3. In a machine of the class described, a conical feeding tube, having an opening in the lower end thereof, a worm operating in said tube, a spirally threaded vessel communicating with the opening in said feeding tube, a spirally threaded cylinder rotatable within said vessel, said cylinder having vertical teeth and a lateral tooth thereon, a pair of rollers above the cylinder, cutting means on said rollers separating said rollers apart, and a collar partly surrounding these rollers provided with an outlet, means on said collar for supplying liquid to said vessel, and means for simultaneously rotat- 130

ing said spirally threaded cylinder and said worm.

4. In a machine of the class described, a conical feeding tube, having an opening in the lower end thereof, a worm operating in said tube, a spirally threaded vessel communicating with the opening in said feeding tube, a spirally threaded cylinder rotatable within said vessel, said cylinder having vertical teeth and a lateral tooth thereon, a pair of rollers above the cylinder provided with interchangeable toothed cutting wheels, and a collar partly surrounding these rollers provided with an outlet, means on said collar for supplying liquid to said vessel, and means for simultaneously rotating said spirally threaded cylinder and said worm.

5. In a machine of the class described, a conical feeding tube, a worm operating therein, a spirally threaded vessel of a shape partly conical and partly circular, communicating with said tube, a spirally threaded cylinder rotatable within said vessel, said cylinder having vertical teeth thereon, a large roller above the cylinder, a smaller roller adjacent said large roller, one of said rollers being provided with a toothed cutting wheel separating said rollers apart, and means for simultaneously rotating said spirally threaded cylinder and said worm.

6. In a machine of the class described, a conical feeding tube, a worm operating therein, a spirally threaded vessel of a shape partly conical and partly circular, communicating with said tube, a spirally threaded cylinder rotatable within said vessel, said cylinder having vertical teeth and ribs thereon, said vertical teeth being of less

thickness than said ribs, a large roller immediately above the cylinder provided with a toothed cutting wheel, a smaller roller adjacent the large roller and also provided with a toothed cutting wheel, and means for 45 rotating said spirally threaded cylinder and said worm.

7. In a machine of the class described, a conical feeding tube, a worm operating therein, a spirally threaded vessel communicating with said tube, a spirally threaded cylinder rotatable within said vessel, said cylinder having ribs or projections thereon, and vertical teeth between said ribs or projections, said vertical teeth being of less 55 thickness than said ribs, a pair of rollers, and means for simultaneously rotating said spirally threaded cylinder and worm and rollers.

8. In a machine of the class described, a conical feeding tube, a worm operating therein, a spirally threaded vessel of a shape partly conical and partly circular, communicating with said tube, a spirally threaded cylinder rotatable within said vessel, said 65, cylinder having teeth thereon, a large roller immediately above the cylinder provided with a cutting wheel, a smaller roller adjacent said large roller and also provided with a cutting wheel, a stand having removable 70 bearings for supporting the lower ends of the shaft of said worm, and said cylinder, and means for simultaneously rotating said spirally threaded cylinder and said worm.

In testimony whereof I have affixed my 75 signature in presence of two witnesses.

LEONIDAS NORZAGARAY.
